UNITED STATES PATENT OFFICE

JACK WILSON, OF CHICAGO, ILLINOIS, ASSIGNOR TO UNIVERSAL DRAFT GEAR ATTACHMENT CO., OF CHICAGO, ILLINOIS, A CORPORATION OF ILLINOIS

CAR COUPLER CONTROLLER

Application filed June 26, 1931. Serial No. 546,957.

The invention relates to devices for laterally positioning an oscillatable car coupler and for disengaging the coupler from that of another car.

5 In accordance with present railroading practice the draw-bar carrying the coupler head is capable of lateral oscillation relatively to the car, and the coupling operation is automatically accomplished. As two cars are brought together it is essential to the 10 automatic coupling action that the draw-bars be so positioned that the coupling elements make direct contact. Official regulations require the provision of means for manually 15 positioning the draw-bar from the side of the car, and this has been accomplished by the use of a pull and thrust rod attached to the draw-bar and projecting beyond the plane of the car side.

20 The regulations also require that means be provided for disengaging the couplers without requiring the operator to enter between the cars, and to this end it has been the practice to attach a turning crank-rod to 25 the releasing element of the coupler, the outer end of the rod projecting to or beyond the plane of the car side.

The principal object of the present invention is to provide for these two operations 30 by means of a single rod. Further objects of the invention are to provide simple and convenient means for actuating the rod both longitudinally and about its axis.

Preferred embodiments of the invention 35 are hereinafter described, and are illustrated in the accompanying drawings, in which

Fig. 1 is a detail plan view of a car and its coupler and of the improved controlling means, a portion of the car being shown in 40 section;

Fig. 2 is a detail end elevation of the car;

Fig. 3 is a detail side elevation of the parts shown in Figs. 1 and 2;

Fig. 4 is a view taken on the line 4—4 of 45 Fig. 2;

Figs. 5 and 6 are sectional details on the lines 5—5 and 6—6, respectively, of Fig. 4;

Fig. 7 is a group of the various elements 50 of the controlling device of Figs. 5 and 6, shown in perspective;

Fig. 8 is a view similar to Fig. 1, showing a different form of controlling device;

Fig. 9 is a view from the line 9—9 of Fig. 8; and

Fig. 10 is a group of the various elements 55 of the controlling device, shown in perspective.

At 15 there is shown an end sill of a car; at 16 its draw-bar; and at 17 its coupler head, of standard type. The coupler head 60 carries the usual elements for engagement with a similar head on an adjacent car, including a locking pin 18 which, as usual, is automatic in its engaging action and is manually released by a raising movement. 65

A rod 19, having a crank-arm 20 at its inner end in engagement with the pin 18 and adapted to raise the latter when turned, is in rotative engagement at its outer end with a depending lever 21, pivotally attached, by 70° means of a bracket 22, to an element of the car body, as shown in the end sill 23.

In the construction disclosed in Figs. 1 to 7 of the drawings, the lever 21 is a rigid bar to which is attached a bearing box comprising the elements 24, 25, carrying the outer end of the rod 19. The elements 24, 25, are inclosed and turn between a pair of lugs 26, 27, projecting laterally from the lever bar, and are secured in place by means of a plate 28, 80 apertured to receive the outer ends of the lugs 26, 27. One of these lugs, as 26, is provided at its outer end with a hook 29 for retaining the upper end of the plate 28, and the other lug 27 is apertured to receive a retaining cotter pin 30.

The outer ends of the elements 24, 25, carry clamping jaws 31, 32, for receiving a down-turned crank-arm 33 of the rod 19. The elements 24, 25, are secured together by a rivet 90 34, and one of them, as 24, carries a depending lug 35, which laterally engages the lever 21 and limits the turning movement of the rod.

For releasing the locking pin 18 the rod 95 19 is turned with the bearing box carried by the lever, and for positioning the coupler head to align it with that of a car with which it is to be engaged the rod is drawn or thrust longitudinally by means of the lever 21. 100

In the form of the device illustrated in Figs. 8 to 10, in place of the one-piece lever bar, as hereinbefore described, there is shown a jointed lever comprising the two parts 36, 37, the former being pivoted to the car body or frame for swinging movement transverse to the car, and the latter being pivoted, as shown at 38, to the member 36 for swinging movement in a direction parallel with the longitudinal axis of the car.

The outer end of the rod 19, in this instance, is upturned, as shown at 39, this end projecting between a pair of jaws 40, 41, formed on the upper end of the lever element 37, and is secured thereto by means of a pivot pin 42. The lever element 37 is provided with a pair of laterally projecting lugs 43, 44, which engage the lower end of the element 36 as a limiting stop.

For the purpose of turning the rod 19 to raise the locking pin 18, the lever element 37 is swung away from the car body, turning on its pivot 38, and for positioning the coupler head the entire lever is swung upon its carrying pivot 45.

I claim as my invention—

1. In a coupler controller, in combination, a depending lever adapted for pivotal attachment to a car body, a rotative bearing box carried by the lever, a rod adapted for attachment to an element of a coupler and projecting through the box and having a crank arm at its outer end, and being secured to the lever against longitudinal movement relative thereto.

2. In a coupler controller, in combination, a depending lever adapted for pivotal attachment to a car body, a rotative bearing box carried by the lever, a rod adapted for attachment to an element of a coupler and projecting through the box and having a crank arm at its outer end, and a pair of clamping jaws carried by the box and engaging the crank arm of the rod.

3. In a coupler controller, in combination, a depending lever adapted for pivotal attachment to a car body, a rotative bearing box carried by the lever, a rod adapted for attachment to an element of a coupler and projecting through the box and having a crank arm at its outer end, a pair of clamping jaws carried by the box and engaging the crank arm of the rod, and a lug carried by the jaws for engaging the lever as a limiting stop.

In testimony whereof I affix my signature.
JACK WILSON.
